DESIGN FOR A RUBBER FLOOR MAT

Harry M. Pryale, Pontiac, Mich., assignor to
Baldwin Rubber Company, a corporation of
Michigan

Application May 18, 1934, Serial No. 51,837

Term of patent 3½ years

To all whom it may concern:

Be it known that I, HARRY M. PRYALE, a citizen of the United States, residing at Pontiac, in the county of Oakland and State of Michigan, have invented a new, original, and ornamental Design for a Rubber Floor Mat, of which the following is a specification, reference being had to the accompanying drawing forming a part thereof, wherein:

Fig. 1 is a plan view of a rubber floor mat, showing my new design.

Fig. 2 is a fragmentary cross-sectional view taken along the line 2—2 of Fig. 1, also illustrating the upper side of the mat.

Fig. 3 is a similar cross-sectional view taken along the line 3—3 of Fig. 1 wherein the fragmentary showings of ornamentation cover the various divisions of the mat as indicated.

I claim:

The ornamental design for a rubber floor mat as shown and described.

HARRY M. PRYALE.
